GARMENT SHAPE MAINTAINING DEVICE

Glenn L. Anderson, University Heights, Ohio

Application December 5, 1947, Serial No. 789,905

4 Claims. (Cl. 223—83)

1

This invention relates to a device adapted to be removably associated with a laundered garment for maintaining its shape, whereby crushing or distortion of portions of the garment, due either to handling thereof or when wrapped or enclosed in a container, is eliminated; more particularly the device is adapted to be related to or associated with a collar attached to a garment and adjacent portions of the latter.

The collars on this type of garment, when laundered, do not have sufficient stiffness to maintain their trim and unique appearance, when handled under ordinary or other circumstances. In many instances, starch is purposely omitted, in the laundering process, so that whatever stiffness is or may be present is due to the connection of the inner member of the collar to the garment neck band. In all these instances, when the laundered garment is packaged (wrapped or boxed) or the package contains two or more of these garments and/or other wearing apparel, the collars become crushed or distorted, due to wrapping and/or handling, so that the user is unable to wear the garment or is highly embarrassed if the garment is worn. It follows that the launderer or cleaner is faced with a serious problem to avoid complaints, which would obviously arise under these conditions. To meet this problem, launderers and cleaners have found it necessary, after the garment is laundered, to associate a removable support or device within the collar, but all supports or devices for attached collars, of which I have knowledge, have been found to be unsatisfactory for the reasons that special care had to be exercised by the worker to properly position each support within the collar and in order to facilitate the insertion of these supports and to minimize the cost, they consisted of an elongated narrow strip formed of thin cardboard and hence unduly flexible and readily bent so as to require careful handling and was therefore inadequate to resist pressure on the collar. As no provision was made for inter-connecting the strip to the collar and because of its high flexibility, the frictional engagement of the strip with the collar material was insufficient to hold them in place incident to ordinary handling of the garment or package.

One object of the invention is to provide an improved shape maintaining device or support for the attached collar of a garment, the device having lateral members adapted to be so connected to the garment that displacement of the device relative to the collar is eliminated.

2

Another object of the invention is to provide an improved collar supporting device which lends itself to quick and ready insertion or positioning in relation to the collar of a garment and interlocking relation with other portions of the garment.

Another object of the invention is to provide an improved device of this character having a collar engaging wall and laterally extending members which interconnect the device to the garment to prevent its displacement, spacedly support the front and back of the garment and maintain the collar elevated relative to the back of the garment to prevent distortion of the front outer portions of the collar.

Another object of the invention is to provide an improved reinforcing device for the collar on a garment, formed from relatively thin sheet cellulose stock and fabricated at low cost and adapted to be removably interlocked to portions of the garment to prevent displacement of the device.

Another object of the invention is to provide an improved reinforcing device for the collar of a garment consisting of an elongated strip formed from relatively thin sheet cellulose stock and having wings adapted to be positioned within the body portion of the garment and a wall adapted to be flexed relative to the wings and positioned within the garment collar to prevent crushing or distortion of the latter.

Other objects of the invention will be apparent to those skilled in the art to which my invention relates from the following description taken in connection with the accompanying drawing, wherein

Fig. 1 is a plan view showing a garment and shape maintaining device embodying my invention in position.

40 Figs. 2, 3 and 4 are sections on the lines 2—2, 3—3 and 4—4, respectively, of Fig. 1.

Fig. 5 is an elevational view of the device.

Fig. 6 is a plan view.

Fig. 7 is an end view.

45 In the drawings, A indicates a garment adapted to be worn by either sex and provided with a collar B consisting of an outer member b and an inner member c suitably attached to the neck band a of the garment A. Fig. 1 shows the garment A in laundered condition with a stiffener C between the folds thereof and a device, indicated as an entirety at 1, associated with collar B and adjacent portions of the garment and adapted to reinforce or maintain them in shape, whereby crushing or distortion of the

collar members *b*, *c*, and/or portions of the garment is eliminated.

The device *1* is cut or stamped by a suitable die from relatively thin flexible cellulose sheet stock and consists of an elongated strip or band, preferably having a width approximately the height of the collar *B* and a length to extend a substantial distance to either side of the attachable ends *c'* of the collar member *c*. While the device *1* may be of a length to extend entirely or approximately entirely around the collar member *c*, its length is preferably somewhat greater than one-half the circumference of the collar member *c* to readily accommodate the device to collars of various sizes and to facilitate the labor of positioning the device, as well as to minimize the amount of material required for each strip, whereby the cost is reduced to a minimum. *2* indicates slots formed in the strip *1* extending inwardly from one edge *1a* thereof (that is, its lower edge when the strip or band is positioned in the garment *A*) extending toward the other edge and inwardly in converging relation, preferably symmetrical to an imaginary center midway the ends of the strip, the inner ends *2a* of the slots *2* terminating in spaced relation equal distances from the edge *1a*. By preference the outer ends of the slots *2* are disposed inwardly of the outer ends of the strip *1*. In this arrangement of the slots *2* I provide wings *3* below the slots *2*, integrally connected at their inner ends to the central section *4* of the strip and a continuous wall *5* integral with the section *4* and extending from end to end of the strip above and outwardly of the slots, the end portions *5a* of the wall *5* having the full width of the strip and hence approximating the height of the collar *B*. In placing the strip in position as shown in Fig. 1, the wall *5* is initially pressed by the operator into engagement with the front and side portions of the collar member *c* and substantially simultaneously the front portion of the collar and shirt front are slightly lifted to raise the front of the garment relative to its back; this operation serves to flex the section *4* and the wall *5* so that the latter lie in substantially concentric relation to the front portion of the collar member *c*, at and along the sides thereof extending circumferentially in opposite directions from the ends *c'*, whereas the wings *3* being free, remain in extended vertical position and hence are moved into the garment under the raised front thereof, to space the latter from the back and fixedly relate the section *4* and wall *5* to the collar member *c*. As the wings *3* are disposed vertically and their upper edges are inclined downwardly and outwardly, the front of the garment, adjacent the collar ends *c'* and outwardly therefrom is supported in spaced relation to the back of the garment and maintain the front portion of the collar in elevated position, so that danger of the tips and outer end portions of the collar member *b* being distorted is eliminated. In this form of construction, with the wings *3* positioned between the front and back of the garment *A*, the strip *1* is interlocked thereto to prevent displacement of the section *4* and wall *5* from the collar member *c*, and thus permits handling of the garment before or after it is wrapped or boxed. By preventing displacement of the strip, less care is required in wrapping a garment or garments and the shape of the collar is maintained until the garment is to be worn.

As the strips *1* are fabricated in a simple man-

ner from flat sheet, thin material and may be stacked face-to-face for shipment, the cost of the material, its fabrication and shipment are reduced to a minimum.

It will be observed that the device *1* is positioned by a single operation and that no portion thereof has to be bent over an adjacent part of the collar or garment in order to effect an interlock therewith. Hence, the device lends itself for easy installation, to reduce labor costs, as well as removal by the user.

As the back of the garment *A* engages face-to-face with the stiffener *C*, a substantially rigid support is provided for the wings *3*.

What I claim is:

1. A garment shape maintaining device consisting of an elongated strip of flexible material formed with slots extending inwardly from the lower edge thereof in converging relation toward the intermediate portion of the strip, that portion of the strip above and outwardly of said slots fitting within and in engagement with the inner wall of the collar of a garment and those portions of the strip below said slots extending outwardly from the opposite sides of the intermediate portion of the strip and vertically positioned between the back and front of the garment and transversely thereof and at opposite sides of the attachable ends of the collar.

2. A garment shape maintaining device consisting of an elongated strip of flexible material formed with slots extending inwardly from the lower edge of said strip inwardly of its opposite ends and in converging relation toward the intermediate portion of said strip and terminating at their inner ends in spaced relation, that portion of the strip above and outwardly of said slots fitting within and in engagement with the inner wall of the collar of a garment and those portions of the strip below said slots extending outwardly from the opposite sides of the intermediate portion of the strip and vertically positioned between the back and front of the garment and transversely thereof and at opposite sides of the attachable ends of the collar, the opposite end portions of the strip having a width substantially equal to the height of the collar.

3. A garment shape maintained device consisting of an elongated strip of flexible material formed with slots extending inwardly from the lower edge thereof and in converging relation toward the intermediate portion of said strip, the inner ends of said slots being spacedly related, that portion of the strip above and outwardly of said slots and the intermediate portion of the strip below the inner ends of said slots being positioned within and in engagement with the inner wall of the collar of a garment and those portions of the strip below said slots extending laterally from said intermediate portion in opposite directions and vertically positioned between the back and front of the garment at opposite sides of the attachable ends of the collar, the flexing of said strip, when the latter is positioned within the collar, serving to maintain the vertically positioned portions substantially transversely of the garment.

4. A device for maintaining the shape of a collar on a laundered garment formed of flexible material and consisting of an elongated strip having a width substantially equal to the height of the collar and formed with elongated slots extending inwardly from one edge of the strip in converging relation, the inner ends of the slots terminating in spaced relation to form an inter-

mediate section between and below said ends, a wall above said ends having lateral portions extending outwardly of said slot ends in opposite directions and wings extending laterally from either side of said intermediate section outwardly and positioned vertically within and transversely of the garment between the front and back thereof and adjacent to the collar and at opposite sides of the attachable ends of the latter, said intermediate section and wall being positioned within the collar and flexed into engagement with the front and opposite contiguous side portions thereof and said wings, due to flexing of said wall and intermediate section, being automatically mov-

5 able into vertical position between the back and front of the garment to prevent dislodgment of the lateral portions of the said wall and to space the front of the garment from the back to prevent curling of the collar tips.
